(57)

CLAIM

The ornamental design for a drum as shown and described.

DESCRIPTION

1.1 : Perspective

1.2 : Perspective

1.3 : Front

1.4 : Back

1.5 : Left

1.6 : Right

1.7 : Top

1.8 : Bottom

Fig. 1.1 is a front top perspective view of the drum; Fig. 1.2 is a rear bottom perspective view thereof; Fig. 1.3 is a front elevational view thereof; Fig. 1.4 is a rear elevational view thereof; Fig. 1.5 is a left-side elevational view thereof; Fig. 1.6 is a right-side elevational view thereof; Fig. 1.7 is a top plan view thereof; Fig. 1.8 is a bottom plan view thereof. The broken lines where present illustrate portions of the drum that form no part of the claimed design.

1 Claim, 8 Drawing Sheets
